(57) **CLAIM**

The ornamental design for a grab bar, as shown and described.

DESCRIPTION

FIG. 1 is a fragmentary perspective view of a grab bar showing our new design;

FIG. 2 is a fragmentary front elevational view thereof;

FIG. 3 is a fragmentary rear elevational view thereof;

FIG. 4 is a fragmentary top plan view thereof; and,

FIG. 5 is a fragmentary bottom plan view thereof.

The portions of the Figures shown in broken lines are not part of the claimed design but are for illustration only.

1 Claim, 2 Drawing Sheets

FIG. 4**FIG. 5**

UNITED STATES PATENT AND TRADEMARK OFFICE
CERTIFICATE OF CORRECTION

PATENT NO. : Des. 536,597 S
APPLICATION NO. : 29/241732
DATED : February 13, 2007
INVENTOR(S) : Viorel Berlovan and Christopher Jon Gilbert
